(57) CLAIM

The ornamental design for a cigarette snuffer and container, as shown and described.

DESCRIPTION

FIG. 1 is a perspective view of a cigarette snuffer and container, showing my new design;

FIG. 2 is a top plan view, the bottom plan view being a mirror image, thereof;

FIG. 3 is an elevational view of one side, the other side elevational view being a mirror image, thereof;

FIG. 4 is an elevational view of one end;

FIG. 5 is an elevational view of the other end; and,

FIG. 6 is a perspective view as in FIG. 1, but showing the removable closure in a detached position, the broken-line representation of a cigarette being included solely for illustrative purposes, forming no part of the claimed design.
